CLAIM

The ornamental design for a pitcher with rocking seal, as shown and described.

DESCRIPTION

FIG. 1 is a top and side perspective view of a pitcher with rocking seal showing our new design;

FIG. 2 is a top plan view thereof;

FIG. 3 is a bottom plan view thereof;

FIG. 4 is a side elevation view thereof, the opposite side elevation being a mirror image;

FIG. 5 is a front elevation view thereof;

FIG. 6 is a rear elevation view thereof;

FIG. 7 is an exploded side elevation view thereof;

FIG. 8 is a cross-section view thereof on line 8—8 in FIG. 2;

FIG. 9 is on a cross-section view thereof on line 9—9 in FIG. 2;

FIG. 10 is a top and side perspective view of a second embodiment thereof;

FIG. 11 is a top plan view of the second embodiment;

FIG. 12 is a bottom plan view of the second embodiment;

FIG. 13 is a side elevation view of the second embodiment, the opposite side elevation being a mirror image;

FIG. 14 is a front elevation view of the second embodiment;

FIG. 15 is a rear elevation view of the second embodiment;

FIG. 16 is an exploded side elevation view of the second embodiment;

FIG. 17 is a cross-section view of the second embodiment taken on line 17—17 in FIG. 11; and,

FIG. 18 is a cross-section view of the second embodiment taken on line 18—18 in FIG. 11.
